B. P. JOYCE

COUNTERPOISE

Filed May 2, 1925

UNITED STATES PATENT OFFICE.

BRYAN P. JOYCE, OF DAVENPORT, IOWA, ASSIGNOR TO DAVID M. KING.

COUNTERPOISE.

Application filed May 2, 1925. Serial No. 27,570.

(GRANTED UNDER THE ACT OF MARCH 3, 1883; 22 STAT. L. 625.)

To all whom it may concern:

Be it known that I, BRYAN P. JOYCE, a citizen of the United States, and a resident of Davenport, county of Scott, and State of Iowa, have invented an Improvement in Counterpoise, of which the following is a specification.

- The invention described herein may be used by the Government, or any of its officers or employees in prosecution of work for the Government, or by any other person in the United States, without payment to me of any royalty thereon, in accordance with the act of March 3, 1883.
- 15 The subject of this invention is a counterpoise intended primarily for use with heavy ordnance but not restricted to such use as it may be employed as a component part of any object mounted for oscillation.
- 20 In the employment of counterpoises with oscillatory bodies, it has been found that their moment curves practically coincide until the body attains an approximate elevation of 45° after which the force exerted by 25 the counterpoise is unduly excessive.

The principal object of the present invention is to provide means to compensate for the variation between the moment curves of the counterpoise and oscillatory bodies. In 30 accomplishing this purpose a plurality of resilient means are employed in the counterpoise which are successively brought into action to counteract the excessive expansive force exerted by the counterpoise as the oscillatory body is elevated above 45°. These 35 counteracting elements or agents are disposed between the casing and the plunger and are actuated at a suitable time during extension of the counterpoise.

40 To these and other ends, my invention consists in the construction, arrangement, and combination of elements described hereinafter and pointed out in the claims forming a part of this specification.

45 A practical embodiment of the invention is illustrated in the accompanying drawing, which is a longitudinal sectional view through a counterpoise constructed in accordance with the invention.

50 Referring to the drawing by numerals of reference:

The counterpoise forming the subject matter of this invention is designed to be mounted in a manner similar to that de-

scribed in Patents No. 1,460,419 and No. 55 1,460,420 issued to me on July 3, 1923.

The counterpoise consists of a cylindrical casing 1, provided with the usual trunnions 2 adapted to be retained in the outer ends of arms fixed to the axis of oscillation of a gun or other body and closed at its upper end by a threadedly adjustable head 3. Reciprocal within the casing is a plunger casing 4 which by means of a ring 5 carries a base 6 in which is threaded an axial piston 65 rod 7. An aperture 8 is provided in the plunger assembly and outer casing 1 for the purpose of temporarily receiving a pin to hold the counterpoise in compressed position against the action of a pair of main springs 70 9—9 separated by a ring 10. One of these springs bears against the ring 5 of the plunger assembly and the other bears against a spacer ring 11 confined by the head 3. This spacer ring serves to center and retain 75 a sleeve 12 having spaced keys 13 receivable between depending lugs 14 in the head 3 and provided with internal longitudinal slots 15 for receiving feathers 16 of the piston head 17 whereby to prevent rotation of the piston 80 during reciprocation. The lower end of the slotted portion of the sleeve constitutes a shoulder 18 which serves to limit movement of a seat 19 apertured to receive the piston rod and formed with a tubular extension 19'. 85 A spring 20 confined between the seat and a base ring 21 threaded in the lower end of the sleeve normally maintains the seat 19 against the shoulder. A spring 22 which is of less strength than the spring 20 is supported on the opposite side of the movable seat 19.

With the counterpoise collapsed as shown, the free end 22' of this spring is spaced a sufficient distance from the piston head 17 95 so that it will not contact therewith to oppose the expansive force until the oscillatory body has obtained a predetermined elevation, preferably 45°.

With the oscillatory body in horizontal 100 position, the counterpoise is collapsed, the weight of the unbalanced end of the body being sufficient to counterbalance the expansive force of the main springs 9—9 in the counterpoise. As the body is elevated the 105 counterpoise is extended, its full effective power being exerted until the spring 22 contacts the piston head 17, at which time the

force exerted is diminished by the energy required to compress the spring 22, the amount of the diminution being predetermined so as to maintain the opposing forces in constant relation. The spring 22 acts in opposition to the main springs until such time as the piston head 17 contacts the end of the tubular extension 19' when the spring 20 comes into action. The strength of the counteracting springs 20 and 22 is so regulated as to compensate for the variation between the moment curves of the counterpoise and oscillatory body. The total resistance necessary to be supplied to compensate for the variations of the opposing forces may be divided into its several components by providing any number of such springs.

In lowering the body the springs tend to collapse the counterpoise until such time as they are fully extended when the full force of the counterpoise comes into play.

While in the foregoing there has been illustrated and described such combination and arrangement of elements as constitute the preferred embodiment of the invention, it is nevertheless desired to emphasize the fact that interpretation of the invention should only be conclusive when made in the light of the subjoined claims.

I claim:

1. A counterpoise embodying telescoping casings, resilient means for extending the counterpoise, a sleeve having a shoulder held at the end of the outer casing by said means, a piston concentric on the inner casing and working in said sleeve, an annular seat formed with a tubular extension disposed in the sleeve, a spring confined between an end of the sleeve and the seat and normally holding the seat against the shoulder, an unconfined spring supported on the opposite side of the seat and extended beyond the tubular extension, and a piston head adapted after initial extension of the counterpoise to first compress the unconfined spring and then to move the seat to compress the confined spring.

2. A counterpoise embodying telescoping casings, resilient means for extending the counterpoise, a confined and an unconfined spring carried with the outer casing, the latter spring being of less strength than the former, and means carried by the inner casing whereby after initial extension of the

counterpoise the springs are successively brought into action to oppose the extension of the counterpoise.

3. A counterpoise embodying casings, a plunger reciprocally mounted therein, resilient means for extending the counterpoise, a confined and an unconfined spring carried with the casing, and means carried by the plunger whereby after initial extension of the counterpoise the springs are successively brought into action to oppose the extension of the counterpoise. 60

4. A counterpoise embodying a casing, a plunger reciprocally mounted therein, resilient means for extending the counterpoise, a plurality of springs carried with the casing, and means carried by the plunger whereby after initial extension of the counterpoise the springs are successively brought into action to oppose the extension of the counterpoise. 70

5. A counterpoise embodying a casing, a plunger reciprocally mounted therein, resilient means for extending the counterpoise, a plurality of resilient means carried with the casing, and means carried by the plunger whereby after initial extension of the counterpoise said last mentioned resilient means are successively brought into action to oppose the extension of the counterpoise. 85

6. A counterpoise embodying a casing, a plunger reciprocally mounted therein, resilient means for extending the counterpoise, resilient means carried with the casing, and means carried by the plunger whereby after initial extension of the counterpoise said last mentioned resilient means are brought into action to oppose the extension of the counterpoise. 90

7. A counterpoise embodying a casing, a plunger reciprocally mounted therein, resilient means for extending the counterpoise, and means carried with the casing and cooperating with the plunger after initial extension of the counterpoise to oppose said extension. 100

8. A counterpoise embodying a casing, a plunger reciprocally mounted therein, resilient means for extending the counterpoise, and means carried with the casing and cooperating with the plunger to oppose the extension of the counterpoise. 105

BRYAN P. JOYCE.
